DESIGN FOR A LIPSTICK HOLDER

William H. Leavin, New York, N. Y.

Application July 9, 1948, Serial No. 147,479

Term of patent 7 years

(Cl. D86—10)

To all whom it may concern:

Be it known that I, William H. Leavin, a citizen of the United States of America, residing in New York, county of New York, and State of New York, have invented a new, original, and ornamental Design for a Lip Stick Holder, of which the following is a specification, reference being had to the accompanying drawing, forming part thereof.

Fig. 1 is a front view of a lip stick holder showing my new design.

Fig. 2 is a side view thereof.

The opposite side of Fig. 1 is substantially the same as that shown in the drawing.

I claim:

The ornamental design for a lip stick holder, substantially as shown and described.

WILLIAM H. LEAVIN.
